Primary Examiner—Ruth McInroy(74) *Attorney, Agent, or Firm*—Scott E. Kamholz; Foley Hoag LLP(57) **CLAIM**

The ornamental design for a vacuum handpiece, as shown and described.

DESCRIPTION

FIG. 1 is a perspective view of a vacuum handpiece showing our new design;

FIG. 2 is a left side elevation view thereof, the right side being a mirror image thereof;

FIG. 3 is a top plan view thereof;

FIG. 4 is a bottom plan view thereof;

FIG. 5 is a rear elevation view thereof; and,

FIG. 6 is a front elevation view thereof.

Broken lines shown in the drawings are for illustrative purposes only and do not form part of the claimed design.
